US0D1068222S

(12) **United States Design Patent** (10) **Patent No.:** **US D1,068,222 S**
(45) **Date of Patent:** **** Apr. 1, 2025**

(54) **FOOTWEAR WITH FULL-LENGTH
MIDSOLE AND CUPSOLE**

(71) Applicant: **Athletic Propulsion Labs LLC**, Los Angeles, CA (US)

(72) Inventors: **Mark R. Goldston**, Beverly Hills, CA (US); **Adam Goldston**, Los Angeles, CA (US); **Ryan Goldston**, Los Angeles, CA (US); **Cody Harris**, Monrovia, CA (US)

(73) Assignee: **Athletic Propulsion Labs LLC**, Los Angeles, CA (US)

(**) Term: **15 Years**

(21) Appl. No.: **29/937,274**

(22) Filed: **Apr. 12, 2024**

(51) LOC (15) Cl. **02-04**

(52) U.S. Cl.

USPC **D2/907; D2/969**

(58) **Field of Classification Search**

USPC D2/896, 902, 904, 905, 907, 908, 920, D2/944, 945, 951-955, 957, 959, 960, D2/969, 972, 973, 974

CPC A43B 1/00; A43B 1/0009; A43B 1/0063; A43B 1/0072; A43B 1/009; A43B 1/02; A43B 1/023; A43B 1/025; A43B 1/028; A43B 1/04; A43B 1/05; A43B 1/10; A43B 1/14; A43B 5/00; A43B 5/06; A43B 5/10

(57) **CLAIM**

The ornamental design for the footwear with full-length midsole and cupsole, as shown and described.

DESCRIPTION

FIG. 1 shows the right view of the claimed design; FIG. 2 shows the left view of the claimed design; FIG. 3 shows the back view of the claimed design; FIG. 4 shows the front view of the claimed design; FIG. 5 shows the top view of the claimed design; FIG. 6 shows the bottom view of the claimed design; FIG. 7 shows the first perspective of the claimed design; and, FIG. 8 shows the second perspective of the claimed design. The ornamental design which is claimed is shown in solid lines in the drawings. The broken lines in the drawings are for illustrative purposes only and form no part of the claimed design. The broken lines showing the laces and the outsole depict portions of the footwear that form no part of the claimed design. The broken lines crossing claimed surfaces depict stitching that forms no part of the claimed design.

1 Claim, 8 Drawing Sheets
